Primary Examiner—Antoine Duval Davis**[57]****CLAIM**

The ornamental design for a container for an oil well stuffing box, as shown and described.

DESCRIPTION

FIG. 1 is a front elevation view of a container for an oil well stuffing box, wherein the broken line showing of a polished rod and a production T is for illustrative purposes only and forms no part of the claimed design;

FIG. 2 is a right side elevation view of the container for an oil well stuffing box, wherein the broken line showing of a polished rod and a production T is for illustrative purposes only and forms no part of the claimed design;

FIG. 3 is a left side elevation view of the container for an oil well stuffing box, wherein the broken line showing of a polished rod and a production T is for illustrative purposes only and forms no part of the claimed design; and,

FIG. 4 is a top plan view of the container for an oil well stuffing box.
